UNITED STATES PATENT OFFICE

2,318,939

GAS BLAST CIRCUIT BREAKER

Alfred Halm, Baden, Switzerland, assignor to
 Aktiengesellschaft Brown, Boveri & Cie., Baden,
 Switzerland, a joint-stock company of Switzerland

Application May 28, 1941, Serial No. 395,639
 In Switzerland June 8, 1940

4 Claims. (Cl. 200—148)

In gas blast circuit breakers the blow valve for extinguishing the arc is generally arranged so that the direction of flow of the gas blast is diverted either whilst passing through the valve itself or before and after the valve. All known arrangements of this kind thus have the disadvantage that the rupturing capacity is diminished because these changes in the direction of the gas blast decrease the velocity of flow and cause eddies to form.

The present invention concerns a gas blast circuit breaker the switch chamber of which is built together with a supporting insulator in the form of a column, the aforementioned disadvantages being overcome by arranging inside the column between the switch chamber and the insulator a blow valve so constructed that the direction of flow of the compressed gas through the valve lies in the axis determined by the supply pipe and the switch chamber.

A constructional example of the invention is illustrated diagrammatically in Fig. 1 of the drawing, Fig. 2 shows a sectional view of the blow valve to an enlarged scale.

The switch chamber *a* of the gas blast circuit breaker is mounted by means of the coupling *b* on the supporting insulator *c* so as to form a column which is carried by the baseplate *d*. This baseplate is built to serve as a compressed gas container and can if necessary be made portable. *e* indicates a voltage isolating switch blade the counter-contact of which is mounted on the supporting insulator *f*. The switch chamber *a* contains one or more circuit interrupting points arranged in series. All insulating parts can be built with or without petticoats. The compressed gas is supplied to the circuit interrupting contacts from container *d* through conduits *g*, *g*₁ and blow valve *h* located in the coupling piece *b*. The control mechanism for regulating the gas supply is not shown in the drawing because it is not an essential element of the invention; it can be operated by hand, pneumatically or electro-pneumatically. The valve disc *i* of the blow valve is fixed in a guide tube *k* which slides in a cylindrical bore inside the valve body. On the outside of the guide tube *k* is a piston *m* located in a slot in the valve body and acted on by the closing spring *n*.

In order to open the blow valve compressed gas is passed from the container *d* through the opening *o* in the valve body to the side of the piston *m* opposite to that on which the closing spring *n* is located. The compressed gas stream can thus flow in a straight line from the gas container through the blow valve to the switch chamber, without being deviated from its course so that favourable conditions for extinguishing the arc are obtained.

The guide tube *k* can also be built as a slide valve which controls gas inlet and outlet openings in the blow valve body and serves to exhaust the switch chamber in the same manner as the bore *p*. This guide tube *k* can also be employed for special control purposes.

I claim:

1. Gas blast circuit breaker the switch chamber of which is built together with a supporting insulator in the form of a column, characterised by the feature that in the coupling piece between the switch chamber and the insulator a blow valve is arranged, said valve being provided with a cylindrical guide for the valve disc and a pressure piston for opening the valve against the action of a closing spring so that the direction of flow of the compressed gas through said valve lies in the direction of the axis determined by the gas supply pipe and the switch chamber.
2. Gas blast circuit breaker as in claim 1, characterised by the feature that the valve disc is fixed in a guide tube on the outside of which an annular piston is arranged.
3. Gas blast circuit breaker as in claim 1, characterised by the feature that the valve disc is fixed in a guide tube which is built in the form of a slide valve which controls gas ports in the valve body.
4. A gas blast circuit breaker having a tubular switch chamber and a tubular supporting insulator arranged in a straight column, a coupling member between the switch chamber and the insulator and a disc blow valve mounted in said coupling member for movement in the direction of the axis of said column so that the direction of movement of the valve disc and of the pressure gas through said column is in the straight line axis of said column.
